UNITED STATES PATENT OFFICE.

GEORGE M. BACON, OF SALT LAKE CITY, UTAH.

CENTRIFUGAL SEPARATOR.

1,321,353.

Specification of Letters Patent.

Patented Nov. 11, 1919.

Application filed February 19, 1917. Serial No. 149,549.

To all whom it may concern:

Be it known that I, GEORGE M. BACON, a citizen of the United States, and a resident of Salt Lake City, in the county of 5 Salt Lake and State of Utah, have invented a certain new and useful Improvement in Centrifugal Separators, of which the following is a specification.

The present invention relates to centrifugal separators, of that type which may be used for removing pulp and slime from water in the process of dressing ore, and for other uses which will be understood from the nature of the invention as hereinafter 15 set forth.

An object of the present invention is to provide a machine of this character by the use of which the separation may be carried on continuously, and without the use of 20 screens and the like.

The invention further aims at the provision of a body adapted to be rotated at a desired speed for separating the relatively heavy substances which are suspended in a 25 fluid medium discharged into the body and depositing the substances against the peripheral wall of the body, the invention providing means for segregating portions of the deposited material, and subsequently 30 discharging the segregated portions without disturbing the accumulation of additional particles or substances against the inner peripheral wall of the body.

The above, and various other objects and 35 advantages of this invention will be in part described, and in part understood, from the following detailed description of the present preferred embodiment, the same being illustrated in the accompanying drawings 40 wherein:

Figure 1 is a view in vertical section, with parts of the same in elevation, of a centrifugal separator constructed according to the present invention.

Fig. 2 is a top plan view of the same.

Fig. 3 is a detail, section taken on the line 3—3 of Fig. 1 through the lower portion of the body of the separator.

Fig. 4 is a detail fragmentary view in section taken transversely through the lower end of said body portion.

Fig. 5 is a detail fragmentary perspective view of the cam employed.

Fig. 6 is a horizontal section taken through 55 the body portion of the separator, partly in

elevation, showing the parts adjusted for receiving the material to be separated.

Fig. 7 is a fragmentary view in section taken through a peripheral portion of the body of the separator, disclosing the same adjusted for segregating portions of the material deposited against the inner wall of the body.

Fig. 8 is a similar view disclosing the parts adjusted for discharging the segregated portions of the deposited material.

Fig. 9 is a similar view disclosing the segregating pockets closed and the parts in position to be advanced into the normal position shown in Fig. 6.

Fig. 10 is a view in vertical section taken through a modified form of the centrifugal separator, parts of the same being shown in elevation.

Fig. 11 is a horizontal view in section through the body portion of the modified form of Fig. 10, showing the modified form of material segregating means closed to the interior of the body.

Fig. 12 is a bottom plan view of the body 80 of the separator, disclosing partly in full lines, and partly diagrammatically, the means for operating the material segregating valves.

Fig. 13 is a fragmentary detail view, enlarged, of a peripheral portion of the body of the modified form of separator, disclosing the valves adjusted to receive a portion of the deposited material.

Fig. 14 is a similar view disclosing the 90 valve closed to the interior of the body.

Fig. 15 is a like view showing the valves adjusted to discharge the segregated material.

Fig. 16 is a detail, enlarged, sectional view 95 taken through one of the valves of the modified form.

Referring to these drawings, wherein like parts are designated by similar characters of reference throughout the several views, 100 20 designates a hollow cylindrical casing or drum provided with a substantially cylindrical core or hub 21 having in one end a plurality of radially extending inlet passages 22 and at its opposite end a plurality of radially extending outlet passages 23. The passages 22 and 23 open to the interior of the drum 20. The lower end of the hub 21 is provided with a supporting sleeve 24 mounted at its lower extremity in a step- 105 110

bearing 25, and is provided upon its upper end with an open-ended cylindrical projection 26. The sleeve 24 is in communication with the radial inlet openings 22, and the 5 cylindrical projection 26 is in communication with the radially extending outlet openings 23.

The peripheral wall of the drum or casing 20 is provided with a plurality of transversely extending closely-spaced-apart slots or openings 27, and the intervening slats or bars have oppositely beveled inner edges 28 for deflecting material through the slots 27. A transparent panel 29 may be mounted 15 in the upper side of the drum or casing 20, through which may be observed the accumulations of the materials which are deposited against the peripheral wall of the drum. A feed pipe 30 projects upwardly through 20 the bearing or base 25 into the sleeve 24 and is adapted to convey the suspended particles or material to be separated. An outlet pipe 31 is arranged over the drum or casing and projects into the hollow projection 25 26. The outlet pipe 31 may be provided with a laterally extending discharge nozzle 32 for carrying off the lighter substances from the interior of the casing or drum 20.

The cylindrical projection 26 of the casing 30 is provided with a relatively large beveled gear 33 which meshes with a pinion 34 mounted on the inner end of a drive shaft 35 which projects radially from one side of the machine, and which is journaled in a 35 suitable bracket 36. The shaft 35 may be driven in any suitable manner, and at the desired speed.

The passage of the material from the drum or casing is regulated by means of a 40 pair of ring valves 37 and 38. The rings 37 and 38 extend from top to bottom of the drum 20, and are provided with through passages or slots 39 and 40 which correspond in width to that of the slots 27 formed in the 45 peripheral wall of the drum. The ring 37 is relatively thick as compared with the thickness of the wall of the drum 20 and the outer ring 38 to provide relatively deep slots or openings forming pockets adapted 50 to receive a relatively large amount of the material which is fed from the body through the slots 27. The rings 37 and 38 are adapted for adjustment upon the drum or casing 20 to arrange the three sets of openings 27, 55 39 and 40 in radial alinement.

The inner ring 37 is provided upon its lower edge with an inturned flange 41 which lies against the underside of the drum or casing 20, and the outer ring 38 is provided 60 with an inturned flange which lies beneath the flange 41, and which has its inner edge flush with the same. The flanges 41 and 42 are provided with like rows of ratchet teeth 43 and 44 which register, and which extend 65 in an opposite direction from that in which

the machine is adapted to be rotated. The casing or drum 20 is provided at its bottom, and preferably at opposite sides, with pairs of pawls 45 and 46, each pair being pivotally mounted upon a pin 47 which projects downwardly from the drum 20. The pawls 45 are arranged in the plane of the upper flange 41, and the lower pawls 46 are arranged in the plane of the lower flange 42. Dogs 48 are hingedly mounted upon the outer ends 70 of the pawls 45 and 46, and are normally held by springs 49 in engagement with the ratchet teeth 43 and 44.

The pawls 45 and 46 are in the form of angled levers which are pivotally mounted 80 upon the pins 47 at their angled portions, and provided with projections or heels 50 at their inner ends.

Surrounding the sleeve 24 beneath the drum or casing is a second large bevel gear 85 51 having a hub 52 which is rotatably mounted on the bearing or base 25, and which extends upwardly about the sleeve 24 and engages the lower side of the drum 20. The upper end of the hub 52 is enlarged to 90 provide a cam 53 provided with diametrically opposed lobes 54, 55, and 56. The lobes 54 are arranged at substantially ninety degrees apart upon the periphery of the cam 53, and the lobes 55 and 56 are arranged between opposed pairs of the lobes 54, leaving diametrically opposed relatively smooth sides to the cam 53 between the opposite pairs of the lobes 54. The lobes 54 are relatively wide so as to simultaneously engage 100 the heels 50 of both of the pawls 45 and 46, while the lobes 55 and 56 are relatively narrow and are adapted to engage the heels 50 of the lower pawls 46 only. Springs 57 are secured to the underside of the drum 20 at 105 one end and engage the outer or radially extending extremities of the pawls 45 and 46 to normally and yieldingly hold the heels 50 thereof against the cam 53. The lobes of the cams 53 are of sufficient height to advance the pawls 45 and 46 sufficiently to step the rings 37 and 38 one tooth forwardly upon each impulse of the adjacent pawl. The teeth 43 and 44 are spaced-apart a distance equal to the spaces between the slots 39 and 110 40 in the rings to alternately register the slots thereof with each other, and with the slats or closed bars lying between the slots. The inner ring 37 terminates at its upper edge flush with the top of the casing or drum 115 20, and the outer ring 38 also terminates in the plane of the top of the casing 20, but is provided at said upper edge with an annular angular strip or beading 58 secured to the outer face of the ring 38 and overhanging 120 the upper edge of the same. A supporting strip 59 is placed annularly over the upper edges of the rings 37 and 38, and in slightly overlapping relation upon the top of the drum 20. The outer edge of the strip 59 130

projects beneath the bead 58 to support the rings 37 and 38 upon the body or drum.

A shell or trough 60 surrounds the body of the separator and is provided with a substantially vertically extending wall spaced from the outer side of the machine for the reception of material which is delivered from the rotating body or drum. The trough 60 is preferably inclined from side to side of the machine and has connection with a discharge means or pipe 61 leading to any suitable point of delivery.

The cam 53 with its gear wheel 51, is rotated by means of a pinion 62 which meshes with the gear wheel 51 and which is carried upon a second shaft 63 projecting radially beneath the body of the machine. The shaft 63 is journaled in suitable bearings 64, a pair of the latter being arranged in spaced-apart relation adjacent to the outer end of the shaft 63. Between the pair of bearings 64 the shaft 63 is provided with a double-faced friction wheel 65 against the opposite sides of which bear a pair of friction rollers 66 mounted for longitudinal adjustment upon a pair of spindles 67. The spindles 67 are mounted in bracket arms 68 which are secured to said pair of bearings 64, and which lie closely against the opposite sides of the wheel 65.

The spindles 67 may be provided at their inner ends with relatively coarse screw-threaded sleeves 69, having worm wheels 70, the latter meshing with worms 71 which are journaled in bracket arms 68 and provided upon adjacent ends with a pair of intermeshing gear wheels 72 for causing the worms 71 to turn simultaneously. Sleeves 73 are threaded on the portions 69 on the spindles 40 and are adapted to advance the rollers 66 across the opposite faces of the friction gear 65 to vary the speed of rotation of the latter.

The main drive shaft 35 is provided with a pair of spaced-apart friction disks 74 which bear at their inner opposite faces against the outer sides of the rollers 66, the latter being thus interposed between the friction disks 74 and the double-faced gear wheel 65. Rotation of the shaft 35 is imparted to the rollers 66, which in turn rotate the friction wheel 65 to turn the shaft 63 in the same direction as that in which the main shaft 35 is driven. Adjustment of the friction rollers 66 varies the relative speeds of rotation of the shaft 35 and the shaft 63 so that the cam 53 may be driven at practically any desired rate of speed with respect to the body or drum of the machine for actuating the pawls 45 and 46.

In operation of the machine, the ring valves 37 and 38 are adjusted into the position shown in Fig. 6, and wherein the pockets or relatively large slots 39 are open to the interior of the drum 20. The outer ends

of these pockets 38 are closed by the slats of the outer ring 38 so that material may pass from the interior of the drum into the pockets 39 and be held therein. When the rings 37 and 38 are in this relative position of adjustment, the pawls 45 and 46 are adjusted as disclosed and shown in Fig. 3, but have the heel portions 50 thereof in position immediately subsequent to engagement with the last lobe 54 of the series. The suspended material is fed through the tube 30 upwardly into the drum 20, and is separated by centrifugal force, whereby the heavier particles of material is deposited against the peripheral wall of the drum. The lighter particles, or fluid-suspending medium, is forced out of the drum through the radial openings 23 and discharged through the spout 32. The heavier material which is deposited against the wall of the drum fills the pockets 39. When the desired amount of the heavier material is deposited against the wall of the drum, which may be ascertained by inspecting the interior of the drum through the transparent panel 29, the rollers 66 may be adjusted to decrease the relative speed of rotation of the shaft 63 to effect the relative movement of the cam 53. This relative backward movement of the cam 53 brings the adjacent lobe 54 into contact with the heels 50 of both of the pawls 45 and 46 to simultaneously advance the rings 37 and 38 one step, and thus entirely close the pockets 37 at their inner and outer ends, as shown in Fig. 7. The ring 37 thus cuts off or segregates a certain portion of the deposited material, and when adjusted into the position shown in Fig. 7, the drum or casing 20 prevents a further outward feeding of the deposited material. The cam 53 now brings the lobes 55 into engagement with the heel of the lower pawl 46 and actuates the same to advance the outer ring 38 one step to register the slots 40 thereof with the pockets 39 of the inner ring. By centrifugal action, the segregated material which is held in the pockets 39 is now discharged into the chute 60.

The third lobe 56 of the cam now engages the heel portion 50 of the lower pawl 46 to advance the outer ring 38 a second time and thus move the openings 40 thereof out of register with the pockets 39. This closes the outer sides of the pockets 39, and when the second lobe 54 simultaneously engages the pawls 45 and 46, the rings are advanced from the position shown in Fig. 9, into their normal position, as shown in Fig. 6. The cylindrical space of the cam 53 now passes beneath the heel portions of the pawls and the rings 37 and 38 remain undisturbed for a length of time sufficient to fill the pockets 37 from the accumulated mass to be deposited against the peripheral wall of the drum 20. The same cycle of operation takes place

when the first lobe 54 is again brought into contact with the pawls 45 and 46. It is of course understood that this action of the pawls is had at the opposite sides of the machine, and that any number of pairs of pawls may be employed, provided that the cam 53 be correspondingly shaped to position the lobes at the desired distances apart, and to provide for the smooth portions of 10 the cam.

It will thus be seen, that after a predetermined amount of material has been deposited against the wall of the drum, the cycle of operation is continuous and the separation may be carried on uninterruptedly, as long as the supply of the suspended material lasts, and until the power is shut off.

In the modified form of the invention, disclosed in Figs 10 to 16, inclusive, the hub 20 of the lower bevel gear wheel 51 is provided upon its upper end with a large spur gear wheel 74^a which is arranged immediately beneath the drum or casing 20. The peripheral wall of the casing 20 is provided 25 with closely spaced-apart cylindrical openings or bearings which open into the interior of the drum 20, and which open to the outer side of the same. Valves 75, of the rotary type, are mounted in these openings 30 in the peripheral wall of the casing 20 and are provided with depending stems 76 which carry on their lower ends pinions 77 arranged in planetary fashion about the spur gear 74^a.

Each valve 75 is in the form of a cylindrical block provided in its opposite sides with longitudinally extending pockets or recesses 78 which, when the valve 75 is rotated, are alternately brought into register with the 40 inner wall of the casing 20 to receive a charge of the deposited material therefrom, and which are subsequently turned into position to open outwardly from the wall of the casing. It will be noted that these recesses or pockets 78 are in the form of concavities providing relatively sharp cutting edges at the opposite sides of the pockets to shear off the material which is segregated or collected in the pockets from the deposited mass within the drum.

The spur gear 74^a may be adjusted as to its relative speed of rotation with respect to the drive shaft 35 by the same means, and in the same manner as the cam 53 of the preferred 55 form may be adjusted. Thus, the pinions with their valves 75 may be turned at the desired speed to register the pockets 78 with the interior of the drum or casing 20 as shown in Fig. 13, to subsequently turn the 60 valves 75 to cut off the segregated material in the pockets 78, and to finally dispose the pocket with the material therein at the outer side of the casing to discharge the material by centrifugal force during the rotation of 65 the casing or body of the device. This latter

position is disclosed to advantage in Fig. 15. It will be noted that by the provision of the valves 75, that as one pocket is discharging the material therefrom, the opposite pocket is receiving a charge of the material from 70 the casing 20. Thus, the action is possibly more rapid than with the construction shown in the preferred form, the latter form being adapted particularly where it is desired to cut off relatively thick or heavy material 75 which is deposited against the peripheral wall of the casing.

In both forms of the invention the material may be continuously deposited against the wall of the drum, and the material is 80 prevented from being discharged too rapidly through the drum by cutting off the flow of the material from the drum and discharging the material in relatively small quantities.

It is of course understood that various 85 changes and modifications may be made in the details of construction of the above-specified forms of the invention without departing from the spirit thereof, and being restricted only by the 90 scope of the following claims.

I claim:—

1. In a centrifugal separator, the combination of a rotatable body, means connected to the body for turning the same, a 95 valve mechanism at the periphery of the body, means for operating the mechanism to open the valves, and an adjustable driving mechanism between the turning means for the body and the operating mechanism for 100 the valves to actuate the same in various desired relations.

2. In a centrifugal separator, the combination of a rotatable body, a gear connected to the body, valves in the wall of the 105 body, operating means for the valves including a second gear, shafts for said gears, means for driving one of the shafts, and an adjustable connection between the shafts for transmitting motion at relatively variable 110 speeds to the shafts.

3. In a centrifugal separator, the combination of a rotatable body, means for turning said body, a plurality of outlet valves arranged at the periphery of the body, rotatable means connected to said valves for actuating the same, and an adjustable connection between said body turning means and said valve-adjusting means for varying the relative speeds of rotation of the body and 115 the valve-adjusting means to actuate the valves at predetermined times.

4. In a centrifugal separator, the combination of a rotatable body, a gear connected to the body, a drive shaft, a pinion on 125 the drive shaft meshing with said gear, a pair of spaced-apart friction disks carried by said drive shaft, valved mechanism arranged at the periphery of the body, valve operating means arranged adjacent to the 130

- body and including a second gear wheel, a second shaft, a pinion on the second shaft engaging the second gear wheel, a double-faced friction gear wheel mounted on said 5 second shaft and projecting into overlapping relation between said friction disks of the drive shaft, and adjustable rollers arranged between the opposite sides of the friction wheel and said friction disks for 10 driving the second shaft from the first and varying the relative speed of rotation of the same.
5. In a centrifugal separator, the combination of a rotatable body, a gear connected to the top of the body, valves arranged at the periphery of the body, valve-operating means arranged below the body and including a second gear, a drive shaft 15 connected to the first gear, a second shaft connected to the second gear, and an adjustable connection between said shafts for driving the same at predetermined relative speeds of rotation for actuating said valves during the rotation of the body. 20
6. In a centrifugal separator, the combination of a rotatable body, a plurality of valves rotatably mounted in the peripheral portion of the body, a gear arranged in concentric relation to the body and adapted to rotate independently thereof, and a plurality of pinions carried upon said rotatable valves and engaging said gear to be actuated thereby, said valves having pockets in their opposite sides adapted to receive material from the body and discharge the same from 30 the outer side thereof. 35

GEORGE M. BACON.
